Thomas H. Wood, Henry S. Hubbell, and Alfred S. Hubbell, of Utica, New York.
Letters Patent No 1513 dated Jan. 7-1862.

The schedule referred to in these Letters Patent and making part of the same.

To all whom it may concern:

Be it known that we Thomas H. Wood of the City of Utica, county of Oneida, State of New York, and Henry S. Hubbell and Alfred S. Hubbell, of the City of Buffalo, County of Erie, and State aforesaid, have invented or produced a new and original design for Cast Iron Tops and Bottoms for Parlor Stoves called the Wild Wood, and we do hereby declare that the following is a full and exact description of the same, reference being had to the accompanying photograph and the letters marked thereon.

the upper top plate. B, the middle top. C, the door frame and D, the door.
E, the bottom.

What we claim as our invention or production and desire to secure by Letters Patent, is the general design and configuration represented in the accompanying photograph.
